HUNTING COAT

Robert E. Lee, Toledo, Ohio, assignor to The Hetrick Manufacturing Company, a corporation of Ohio

Application January 12, 1942, Serial No. 426,430

1 Claim. (Cl. 2—94)

This invention relates to coats but more particularly to hunting or sport coats which are provided with raglan sleeves and in which the body portion of the coat and sleeves is of relatively heavy stiff material, such as water-proof canvas, and an object is to provide a coat of the above character with means which will facilitate the raising of the arms and eliminate the usual objection in such garments due to lifting of the lower portion of the coat body when the sleeves are raised.

Another object is to provide a hunting coat with an insert underneath each of the sleeves of such character as to enable the sleeves to be raised without affecting the body portion of the coat thereby facilitating the handling of a gun or rifle without impedance even when the coat is weighed down with shells, game, etc.

Other objects and advantages will hereinafter appear and for purposes of illustration but not of limitation, an embodiment of the invention is shown on the accompanying drawing in which—

Figure 1 is a front view of a hunting coat provided with worsted knit inserts under each of the sleeves, the sleeves being of the raglan type;

Figure 2 is an enlarged fragmentary detail showing one of the sleeve inserts in partly extended position; and

Figure 3 is a view similar to Figure 2 with the sleeve in substantially fully raised position.

The illustrated embodiment of the invention comprises a hunting coat having a body 10 which may be of relatively stiff heavy material, such as water-proof canvas. The coat is provided with gusseted pockets 11 having side openings 12 and flaps 13 which are adapted to contain or conceal shells and the like ordinarily carried by hunters and which usually are relatively heavy. Attached to the body portion are raglan type sleeves 14, these being attached in the usual manner as by sewn seams 15. Extending across the back of the coat adjacent the lower portion is a game pocket 17, the flap of which is connected by detachable fasteners 18 disposed along a line approximately intersecting the sleeve arm pits.

Heretofore considerable difficulty has been occasioned in hunting coats of the above type equipped with raglan type sleeves for the reason that when the sleeve is raised as, for example, for shooting, the lower portion of the coat must be raised accordingly. This is quite troublesome particularly when the pockets are overweighed down with shells, game, etc. To over-

come that difficulty, gussets have been placed underneath the sleeves, but these are objectionable because of the bulkiness of these inserts when the sleeves hang down against the sides of the coat.

5 In accordance with this invention, an insert 16 of relatively light weight foraminous fabric material of generally oval shape is sewed respectively to the underside of the sleeve and to the adjacent portion of the body. Preferably the insert is of 10 worsted knit material which is sufficiently elastic, is foraminous to afford the desired ventilation, is free from uncomfortable bulkiness, and affords the necessary warmth. As shown, the 15 insert is of two thicknesses of knit material for strength and warmth. The worsted material is ribbed in the longitudinal direction of the insert to afford the maximum elasticity to the material and also facilitate moving the sleeve toward and away from the body portion 10.

20 It will be manifest that when the sleeves are against the side of the body portion 10, the worsted knit insert 16 will return to its normal unstretched position occupying a minimum 25 amount of space and eliminating any bulginess or uncomfortable feeling to the wearer. With the above described insert 16 in place the arms can be raised easily and in the normal manner without interference in spite of the relatively 30 stiff material of the body portion of the coat and furthermore without lifting the lower portion of the coat which is normally required. Thus, even when the game pocket 17 and pockets 11 are filled, the hunter has free use of his arms 35 for handling a gun.

It is to be understood that numerous changes in details of construction, arrangement and operation may be effected without departing from the spirit of the invention especially as defined 40 in the appended claim.

What I claim is:

A hunting coat of the character described, comprising a body portion of relatively stiff canvas material having a game pocket in the portion thereof below the armpits, raglan sleeves of said canvas material secured to the body portion, the adjacent edges of the sleeves and body portion being unsecured to one another in the armpit regions whereby to affect ovate cut-outs 45 so that when the sleeves are raised and lowered, the upper edges of the undersides of the sleeves swing in arcs about axes constituted by the uppermost points of the cut-outs, a pair of worsted knit, ovate, longitudinally ribbed armpit inserts 50 having their longitudinal edges respectively se-

cured to said adjacent edges so as to close said cut-outs, each insert being, in unstretched condition, substantially wider than the distance between said adjacent edges, and being normally narrower than such distance when the sleeves are substantially raised, whereby when said sleeves are brought down from a raised position

5 to a lowered position and said inserts pass through a substantially flat, unstretched condition, the arcs through which the edges of the sleeves pass bring such edges below the major portions of the inserts, whereby to ensure against downward sagging of the inserts.

ROBERT E. LEE.
